UNITED STATES PATENT OFFICE.

BRYAN P. JOYCE, OF DAVENPORT, IOWA, ASSIGNOR TO THOMAS A. CONLON, OF SILVER SPRING, MARYLAND.

GUN CARRIAGE.

Application filed July 31, 1924. Serial No. 729,322.

(GRANTED UNDER THE ACT OF MARCH 3, 1883; 22 STAT. L. 625.)

The invention described herein may be used by the Government, or any of its officers or employees in prosecution of work for the Government, or by any other person in the United States, without payment to me of any royalty thereon, in accordance with the act of March 3, 1883.

The present invention relates to gun carriages, and particularly, to elevating mechanism and top carriage for that class of guns which are adapted to accompany infantry troops or for use in mountainous regions.

Guns of this type must possess extreme mobility and to this end the various parts must lend themselves to ready dismantling and assembly for transportation by hand. In addition, the reduction of the component parts to a minimum number necessitates a construction of the gun carriage so that the gun cradle may be properly mounted and dependably held during recoil, counter-recoil, and elevation.

To this end, the present invention is designed to provide a novel and unique top carriage constructed to effectively support and lock the gun cradle during firing and which includes the operating elements for conveniently actuating an elevating mechanism from a position adjacent the breech of the gun.

There is also provided an elevating mechanism in which provision is made, specifically, by a spherical nut which is yieldingly confined in and rotatable with a cage, to eliminate binding action upon operation of the mechanism.

To these and other ends, my invention consists in the construction, arrangement, and combination of elements, described hereinafter and pointed out in the claims forming a part of this specification.

A practical embodiment of my invention is illustrated in the accompanying drawings, in which,—

Fig. 1 is a view in side elevation of a gun carriage embodying my invention;

Fig. 2 is a plan view of the same;

Fig. 3 is a plan view of the elevating mechanism;

Fig. 4 is a vertical sectional view of Fig. 3;

Fig. 5 is a sectional view taken on the line 5—5 of Fig. 4;

Fig. 6 is a detail view of the spherical nut;

Fig. 7 is a detail view of one of the segments;

Fig. 8 is a plan view of the top carriage;

Fig. 9 is a view in side elevation of the top carriage;

Fig. 10 is a rear view of the same;

Fig. 11 is a detail perspective of the trunnion cap;

Fig. 12 is a perspective of the locking lever;

Fig. 13 is a detail view of the trunnion bearing; and

Fig. 14 is a fragmentary longitudinal sectional view of the recoil cylinder.

Referring to the drawings by characters of reference:

The gun barrel A is reciprocally mounted in a cradle B, which is herein shown as a casing surrounding the barrel and supported at its rear in a top carriage C, which top carriage is mounted on trails D, having the usual spade E. The trails are secured to a housing F which embrace a partially threaded axle G connecting wheels H. Carried by the axle housing F is a casing I, in which is disposed the elevating mechanism K, to pivotally support the forward portion of the cradle B above the axle.

Any suitable mechanism may be employed for counteracting the recoil and counter-recoil movement of the gun and for returning the gun to battery. That herein shown is similar to the subject of my invention as disclosed in Patent No. 1,480,557, and comprises a recoil spring 10, embracing the gun within the cradle and compressed against a bearing 11 by a cap 12, secured to the forward end of the barrel. Similarly, a cylinder 13 filled with any suitable fluid is rigidly secured to the gun cradle and receives a piston 14 retractable with the gun during recoil and carrying a valve mechanism 15 of any desired character.

The rear end of the cradle is provided with a band 16, having trunnions 17, which are disposed in trunnion blocks 18, formed on the top carriage C.

The top carriage is a casting having op-

positely disposed bearings 19, embracing the trails D which are preferably cylindrical and formed with flanges 20 for holding the carriage against rearward movement.

5 Referring to Figure 8, the upper structure of the carriage approximates in outline, a truncated pyramid having side walls 21, a front wall 22, and a rear wall 23. The truncated face of the carriage is formed in-
10 to a longitudinally extending U-shaped seat 24, in which the trunnion band 16 is positioned, thereby disposing the breech 25 of the gun in rear of the top carriage.

15 As will be seen from Figures 9 and 10, the side walls 21 are inclined only through a portion of their height whence they extend vertically to form the sides of the seat 24 and blend with the front and rear walls, which extend laterally thereof, (see
20 Fig. 8) to form the trunnion blocks 18, (see Fig. 13).

25 The front ends of the trunnion blocks are bifurcated (see Fig. 8) to form a hinge butt 26, its central portion is depressed semi- circularly as at 27 (Fig. 13) to form the trunnion bearing, while the rearmost portion is terminated beyond the rear wall 23 in an attenuated extension 28. Pivoted to the butts 26 are trunnion caps 29, centrally
30 raised as at 30 to accommodate the trunnions and extending beyond the rear walls where they are bifurcated to form butts 31 (Fig. 9) for the reception of a locking lever 32, which is also bifurcated to straddle the
35 extension 23, in order to rigidly maintain the trunnion cap in locked position. The lever is formed with an ear 33, registering with a lateral projection 34 on the rear wall, both of which are apertured to receive a
40 snap hook 35, loosely carried on a chain 36 secured to the side wall in any convenient manner.

45 The top carriage is further cast with a gear casing 37, formed with a guide collar 38 (see Fig. 3) for the reception of a shaft 39, which extends forwardly at an angle to the axle of the gun to be operatively connected to the elevating mechanism K. The gear casing 37 is also formed on its outer side with a guide 40 for the reception of a shaft 41, on the outer end of which is squared a hand wheel 42. (see Fig. 2) by means of which gear 43 is actuated to rotate the shaft 39, through engagement with
50 a gear (not shown) fast on the inner end of the shaft 41.

55 The elevating mechanism is enclosed in the casing I, which comprises a casting 45 formed integrally with the axle housing F and secured to the casting in any suitable manner is a bottom plate 46.

60 Supported by the bottom plate is a bowl-shaped pinion 47, to which is keyed an inverted similarly shaped cover plate 48 formed with an annular flange 49 for seat-

70 ing the plate on the casting 45. The pinion 47 and cover plate 48 in assembly constitute a housing for confining a spherical nut 50, constrained to rotate therewith by means of pins 51 carried by the cover plate and inserted in ring segments 52 disposed in grooves 53 in the spherical nut. The pins may be inserted through an aperture 54 in the casing 45 and the aperture closed by a screw 55.

75 Passing through the casing I and spherical nut 50 is a threaded shaft 56, pivotally attached to a band 57, encircling the gun cradle B and through which the gun is adapted to be elevated or depressed when the housing and nut are rotated through the pinion 47 by a beveled gear 58, secured to the shaft 39 and meshing with said pinion. The spherical nut, being yieldingly held, will be capable of limited universal
80 movement to prevent binding action during operation of the elevating mechanism.

85 The gun is traversed about the spade E as a center by a hand wheel 58 (see Fig. 1) as disclosed in my Patent, No. 1,480,556.

90 The usual sighting mechanism may be mounted on the trunnion or gun cradle in any convenient manner, so that it will be moved with the gun during elevation and depression.

95 For convenience in transportation the gun cradle is removed by elevating the piece until the threads on the elevating shaft clear the wall nut and then unlocking the trunnion caps, while the gun itself may be disengaged from the cradle if desired. The carriage is dismantled by removing the left wheel and unthreading the axle from the axle housing. The trail with the axle housing, the elevating mechanism, and the top carriage form one load, while the wheels form another.

100 While in the foregoing there has been illustrated and described such combination and arrangement of elements as constitute the preferred embodiment of my invention, it is nevertheless desired to emphasize the fact that interpretation of the invention should only be conclusive when made in the light of the subjoined claims.

110 I claim:

1. In combination with an axle housing, a trail and a top carriage, an elevating mechanism including a casing carried by the housing, a bowl-shaped pinion within the casing, a bowl-shaped cover plate keyed to the pinion, a spherical nut embraced by the pinion and cover, said nut formed with grooves, ring segments within the grooves, pins carried by the cover and inserted in the segments whereby to yieldingly connect the cover and the spherical nut, a threaded shaft passing through the nut, and means connected with the top carriage for rotating the pinion.

2. In combination with an axle housing, a trail and a top carriage, an elevating mechanism including a casing carried by the housing, a bearing rotatable within the casing, a spherical nut within the bearing and yieldingly held to rotate therewith, a threaded shaft passing through the nut, and means connected with the top carriage for rotating the bearing.
- 5 3. In combination with a trail, a top carriage and an axle housing, an elevating mechanism including a casing carried by the housing, a bearing rotatable within the casing, a spherical nut rotatable with the bearing, a threaded shaft passing through the nut, and means connected with the top carriage for rotating the bearing.
- 10 4. In combination with a gun carriage, an axle housing, a trail fast on said housing, an elevating mechanism supported by the housing, a top carriage supported by the trail, a
- 15 gear casing formed on the top carriage, and a shaft connecting the casing and the elevating mechanism.
5. A top carriage for guns including trail 25 bearings for supporting the carriage, a truncated pyramidal cradle mount formed with trunnion blocks, each having an attenuated extension, trunnion caps hingedly secured to the blocks, a bifurcated locking lever hingedly secured to the cap and adapted to straddle the extension and snap hooks for securing the lever to the mount.
- 10 6. A top carriage for guns including trail 35 bearings for supporting the carriage, a truncated pyramidal cradle mount formed with trunnion blocks, each having an attenuated extension, trunnion caps hingedly secured to the block, and a locking lever hingedly secured to the cap, said locking lever being 40 bifurcated to straddle the extension.

BRYAN P. JOYCE.
